UNITED STATES PATENT OFFICE.

CHARLES H. CUNO, OF MERIDEN, CONNECTICUT.

GAS-ENGINE STARTER.

1,078,260.

Specification of Letters Patent.

Patented Nov. 11, 1913.

Application filed January 27, 1913. Serial No. 744,287.

To all whom it may concern:

Be it known that I, CHARLES H. CUNO, a citizen of the United States, residing at Meriden, New Haven county, State of Connecticut, have invented certain new and useful Improvements in Gas-Engine Starters, of which the following is a full, clear, and exact description.

My invention relates to an improved gas engine starter, the chief objects being to attain simplicity of construction and operation without sacrifice to durability and reliability.

In the accompanying drawings: Figure 1 is a central longitudinal section of one part of my invention. Fig. 2 is an end elevation of another part of my invention. Fig. 3 is a section thereof on the line $x-x$.

In the form shown in the drawings, my invention is designed to supply gas to a four-cylinder motor, although it should be understood and will be apparent that it may be employed with an engine having any number of cylinders. It should also be understood that I am showing my invention in a preferred form only and that various modifications and variations may be resorted to without departing from the spirit and scope thereof.

1 represents a cylinder for measuring the gas which is to be delivered to the engine cylinder or cylinders. 2 represents a piston therein having a suitable packing means.

3 represents a hollow piston-operating rod which projects outwardly and may be provided with a handle 4. Around this rod 3 is located a short spring 5, the function of which will be later described.

6 is an adjustable head at the outer end of the cylinder, which constitutes a movable abutment which may be adjusted to any desired position, said abutment being located in the path of movement of the spring 5 so that as the piston moves outwardly, the spring 5 will abut against the same, whereby further movement of the piston will be resisted so that any gas tending to force the piston out farther will increase in pressure within the cylinder 1 before the piston has reached the limit of its outward excursion.

7 is an inlet pipe which is connected with any suitable source of gas supply under pressure.

8 is a valve controlling the passage through the inlet 7, said valve 8 being suit-

ably packed as at 9 to prevent leakage and being provided with a suitable handle 10 preferably located adjacent to the handle 4 for the convenience of the operator. The inlet passage leads from the valve 8 into the bottom of the cylinder 1, the said passage being further controlled by a valve 11 which is normally held open by means of a spring 12 so that any gas entering through the inlet 7 and past the valve 8 may pass freely into the measuring cylinder beneath the piston 2. The valve 11 is provided with a rod 14 which passes up into the tubular rod 3 and is provided with an abutment or shoulder 15 which is engaged by a shoulder 16 at the lower end of the tubular rod 3 when the piston 2 has approximately reached the limit of its outward movement so that the last partial outward movement of the piston 2 will operate on the rod 14 to pull the valve 11 into the closed position. The valve 11 will then stay closed under the pressure of the gas entering through the inlet 7. It should be understood that the end of the spring 5 engages the head 6 considerably before the shoulder 16 engages the shoulder 15 of the valve 11, hence, the last part of the outward movement of the piston is resisted by the spring pressure 5, which, of necessity, requires additional pressure of the gas back of the piston 2 to move it the last part of its outward excursion. This resistance may be varied by shifting the head 6, the aim being to have the piston move a certain predetermined distance so as to guarantee a fixed volume, the pressure within said fixed space being determined by the resistance of the spring 5 and the position of the head 6. The spring 5, being very much shorter than the full stroke of the piston 2, guarantees the easy movement of the piston for the greater part of its outward stroke, the pressure being built up within the cylinder 1 and beneath the piston 2 on the last part of said stroke.

17 is an outlet passage at the bottom of the cylinder 1 which leads to a suitable distributor, a preferred form of which will now be described. Referring to Fig. 3, the outlet 17 is connected, by means of a suitable pipe (not shown), with an inlet 18 of a distributor. This inlet 18 leads to a valve 19 which is normally held closed under the action of a spring 20. This valve 19 is of substantially greater cross-sectional area than the inlet opening 18 and its main body

is preferably cylindrical, as shown, being provided with one or more gas ducts in the sides, as indicated at 21-21. The valve 19 operates, and preferably carries, what I will term a valve-opener which, in this instance, is in the form of a plate 22.

23-23 are distributing tubes provided in a number corresponding to the number of cylinders to which it is intended to feed the gas. Each of these distributing tubes is provided with a check valve 24, each of which is normally held closed by means of a suitable spring 25. Assuming that the piston 2 of the measuring device has been pushed back by gas entering through the inlet 7 and past the valve 11, such gas as is contained underneath the piston 16 may now be forced through the several distributing tubes 23 by simply pressing in on the handle 4, forcing the piston 2 ahead and forcing the gas contained within the measuring cylinder 1 through the outlet 17 and into the distributor inlet 18, unseating valve 19, which simultaneously unseats the several check valves 24 shown, so that the forwardly impelled gas may readily and freely flow to the several cylinders through the pipes 23, giving to each an initial starting charge which may be ignited by the usual igniter means (not shown) employed in connection with gas engines. When the piston 2 has been pushed entirely in, its forward end engages a shoulder 26, which, in this instance, may be a mere cotter pin passed through the rod 14, so that the end of the forward movement of the piston 2 will positively open the valve 11. In the preferred construction, the outlet 17 from the cylinder 1 is so arranged that when the piston 2 has been pushed fully in and held, it will cover said outlet and thus prevent any gas from flowing through from the supply in the event the valve 8 should inadvertently be left open. While the valve 8 should be closed before the piston 2 is forced in, if it should be left open, the only effect would be (in the event pressure were removed from the handle 4) to force the piston 2 outwardly again so that a second charge could be measured ready to be delivered to the cylinders by a second forward movement of the piston 2. In some instances, such as starting a motor in cold weather, it may be desirable to force two charges into the engine, hence, by this arrangement, this can be done by simply leaving the valve 8 open and allowing the measuring cylinder to be filled twice so that a double charge may be forced into the engine, after which the valve 8 should, of course, be closed. In the event the operator should forget to close the valve 8, he would be visibly warned of his failure so to do by reason of the fact that the handle 4 would be forced outwardly.

65 From the foregoing it will be seen that

only a definite predetermined quantity of gas can be delivered to the engine upon a single cycle of operation of the apparatus described. I have also shown in combination with the foregoing parts, means whereby the user may employ the stored gas for running the engine in the event it is desired to warm up the engine preparatory to having it run on its own normal fuel, or for any other reason. This apparatus comprises an outlet 27 which leads to the usual intake manifold (not shown) through which the usual gas is supplied to the engine. This outlet 27 is normally closed by valve 28 held seated by a spring 29.

30 is a button or handle at the end of a rod 31, said rod being held retracted in any suitable way as by a spring 32, the forward end of said rod being arranged to engage the valve 28 so that when the rod is pushed in, said valve 28 will be opened. The main gas inlet 7 has a continuation which leads to the valve 28, hence, after the engine has been started, the operator may press against the button or handle 30 and unseat the valve 28 so that the stored gas will flow directly through the outlet 27 into the engine manifold.

It will be observed that only an absolutely predetermined quantity of gas can possibly reach the engine cylinders since the valve 11 is not only held closed by the pressure of the gas back of it when the piston 2 has been fully extended, but said valve 11 is also pulled closed mechanically before the gas pressure is applied directly thereto for the purpose of holding it closed, this pulling closed of the valve 11 being effected by the action of the piston 2 against the rod 14.

The comparatively light action of the piston 2 and its relatively large surface area guarantees the effective operation of the apparatus even though the pressure in the storage tank is very light, as is the case when the storage tank is nearly exhausted; and it will furthermore be seen that a predetermined and accurately measured volume of gas may be secured without the employment of any pressure-reducing valve or apparatus such as frequently employed in other apparatus of this character.

What I claim is:

1. In a gas engine starter, a measuring cylinder, a piston therein, means for yieldingly checking the receding movement thereof, a gas inlet leading into said cylinder in front of said piston for admitting gas under pressure, a valve for said inlet, with means for positively closing said valve by the action of the piston, and a manually operable means for permitting said piston to be advanced to expel the gas therein.

2. In a gas engine starter, a measuring cylinder, a piston therein, means for yieldingly checking the receding movement there-

of, a gas inlet leading into said measuring cylinder in front of said piston for admitting gas under pressure, an outwardly opening valve therefor, with means for closing said valve by the action of the piston and holding the same closed by the external gas pressure against the same until the piston is advanced, and means associated with the piston for unseating said valve when said piston is advanced, and with means for manually advancing said piston.

3. In a gas engine starter, a measuring cylinder, a piston therein, adjustable means for yieldingly checking the receding movement thereof, a gas inlet leading into said cylinder in front of said piston for admitting gas under pressure, a valve for said inlet, with means for positively closing said valve by the action of the piston, and a manually operable means for permitting said piston to be advanced to expel the gas therein.

4. In a gas engine starter, a measuring cylinder, a piston therein, means for yieldingly checking the receding movement thereof, a gas inlet leading into said cylinder in front of said piston for admitting gas under pressure, a valve for said inlet, with means for positively closing said valve by the action of the piston, a manually operable means for permitting said piston to be advanced to expel the gas therein, and a gas distributing means associated with said measuring cylinder, said distributing means including a valved passage having two outwardly opening valves therein.

5. In a gas engine starter, a measuring cylinder, a piston therein, means for yieldingly checking the receding movement thereof, a gas inlet leading into said cylinder in front of said piston for admitting gas under

pressure, a valve for said inlet, with means for positively closing said valve by the action of the piston, a manually operable means for permitting said piston to be advanced to expel the gas therein, and a gas distributing means associated with said measuring cylinder, said distributing means including a valved passage having two outwardly opening valves therein, one valve being mechanically opened by the movement of the other valve.

6. In a gas engine starter, a measuring cylinder, a piston therein, means for yieldingly checking the receding movement thereof, a gas inlet leading into said cylinder in front of said piston for admitting gas under pressure, a valve for said inlet, with means for positively closing said valve by the action of the piston, a manually operable means for permitting said piston to be advanced to expel the gas therein, and a gas distributing means associated with said measuring cylinder, said distributing means including a valved passage having two self-closing outwardly opening valves therein, one valve being mechanically opened by the movement of the other valve.

7. In a gas engine starter, a gas measuring device, with means for manually expelling gas contained therein therefrom through a distributing outlet, and a distributing device associated with said distributing outlet including two self-closing outwardly opening valves, one of said valves being opened by the movement of the other, the latter being opened by the pressure of gas delivered thereto from the measuring device.
